UNITED STATES PATENT OFFICE.

HUBBARD F. HURD, OF TROY, NEW YORK, ASSIGNOR TO CLUETT, PEABODY & CO., INC.,
OF TROY, NEW YORK, A CORPORATION OF NEW YORK.

SOFT-FOLD COLLAR.

1,311,520.

Specification of Letters Patent. Patented July 29, 1919.

Application filed January 10, 1919. Serial No. 270,516.

To all whom it may concern:

Be it known that I, HUBBARD F. HURD, a citizen of the United States, residing at Troy, county of Rensselaer, and State of New York, have invented certain new and useful Improvements in Soft-Fold Collars, of which the following is a specification.

Reference may be had to the accompanying drawings, and the reference characters marked thereon, which form a part of this specification. Similar characters refer to similar parts in the several figures therein.

This invention relates to fold-collars, and is more particularly adapted for what are known as soft fold-collars.

The principal object of the invention is to provide invisible means whereby the end-portions of the folded-over top of the collar can be detachably secured to the band of the collar whereby said ends of the folded-over top may be held in proper position in use.

For accomplishing this same purpose in soft fold-collars, it has been proposed to permanently attach to the under or rear side of the folded-over top various forms of fastening devices, the band being provided with fastening means coöperative with such fastening devices on the ends of the folded-over top.

While such fastening devices, which have been of various kinds permanently attached to the under or rear side of the folded-over top, are themselves invisible in use, their presence is frequently indicated by dents or impressions which they make in the outer facing-ply of the top when the collar is ironed in the laundrying process.

The more particular object of my invention is to prevent the forming of noticeable dents or impressions in the outer facing-ply of the folded-over top when the collar is ironed in the laundrying operation.

Other objects will appear in connection with the following description.

Figure 1 of the drawings is a front view in perspective of a soft fold-collar embodying my invention, one of the front end-portions of the folded-over top being folded back to expose the fastening means whereby it can be detachably connected to the band.

Fig. 2 is a cross-section of one end-portion of the folded-over top taken on the broken line 2-2 in Fig. 1 through the fastening device.

Fig. 3 is a cross-section taken through the

fastening member on one end of the band of the collar.

Referring to the drawings wherein the invention is shown in preferred form, 1 is the band, and 2 is the folded-over top of the 60 collar.

The top may be connected with the band by any of the usual methods whereby the top is adapted to be folded over upon or outside of the band.

The top of the collar is made of a plurality of plies of fabric; and I have shown in the drawings a top made of an inner or rear facing-ply, 3, and an outer or front facing-ply, 4, and an interlining, 5.

The ends of all these plies are inturned between the facing-plies, 3 and 4 as shown at 6, in Fig. 2, the folded edge-portions of the plies being secured together in the usual manner by stitching, 7.

Attached to each end of the band, 1, is a post-member, 8, of a snap-fastener, which post-member is coöperative with a socket-member, 9, of a snap-fastener, which socket-member is attached to the neighboring end 80 of the folded-over top in position to co-operate with said post-member, 8.

This socket-member, 9, is inserted through and permanently attached to both the inner or outer facing-ply, 3, and the inturned 85 edge-portion thereof as shown in Fig. 2, thereby giving said socket-member a secure anchorage upon the folded-over top without the extension of the socket-member through either the outer facing-ply, 4, or the interlining-ply, 5.

The inturned edge-portions, 6, of the outer facing-ply, 4, and interlining-ply, 5, extend over and cover the inner end of the socket-member, 9, thereby forming a pad between 95 the inner end of the socket-member and the outer facing-ply, 4. The pad or cushion thus formed serves to distribute the thrust of the socket-member against the outer facing-ply during the ironing process in the 100 laundrying operation, so that said outer facing-ply is not noticeably dented, impressed or disfigured due to the presence of the socket-member.

If desired, the interlining-ply, 5, may be 105 omitted.

In use the snap-fasteners are operated in the usual manner by telescoping their members together or apart; and when the members of the fastener are assembled together 110

they securely hold the ends of the folded-over top in proper position in use.

While I have shown and prefer to employ snap-fasteners for this purpose, it will be apparent that the invention is applicable to various kinds of fastening devices which are open to the same objection as snap-fasteners are, which objections may be overcome in the manner above described.

10 What I claim as new and desire to secure by Letters Patent is:

1. A fold-collar having a band and a folded-over top, said band being provided near one end with fastening means, and said top having near its corresponding end an attached fastening member coöperative with said fastening means of the band, said top being made of a plurality of plies of fabric with inturned edge-portions, said fastening member being permanently attached to the rear facing-ply of the top, and both the front facing-ply of the top and its inturned edge-portion extending over and covering the inner end of said attached fastening member.

2. A fold-collar having a band and a folded-over top, said band being provided near one end with fastening means, and said top having near its corresponding end an attached fastening member coöperative with said fastening means of the band, said top being made of a plurality of plies of fabric with inturned edge-portions, said fastening member being permanently attached to both the rear facing-ply of the top and its inturned edge-portion, and both the front facing-ply of the top and its inturned edge-portion extending over and covering the inner end of said attached fastening member.

front facing-ply of the top and its inturned edge-portion extending over and covering the inner end of said attached fastening member.

3. A fold-collar having a band and a folded-over top, said band having near one end a post-member of a snap-fastener, and said top having near its corresponding end a socket-member of a snap-fastener coöperative with said post-member on the band, said top being made of a plurality of plies of fabric with inturned edge-portions, said socket-member being fixedly attached to the rear facing-ply of the top, and both the front facing-ply of the top and its inturned edge-portion extending over and covering the inner end of said socket-member.

4. A fold-collar having a band and a folded-over top, said band having near one end a post-member of a snap-fastener, and said top having near its corresponding end a socket-member of a snap-fastener coöperative with said post-member on the band, said top being made of a plurality of plies of fabric with inturned edge-portions, said socket-member extending through and being permanently attached to both the rear facing-ply of the top and its inturned edge-portion, and both the front facing-ply of the top and its inturned edge-portion extending over and covering the inner end of said socket-member.

In testimony whereof I have hereunto set my hand this 2nd day of January, 1919.

HUBBARD F. HURD.
